Primary Examiner — Elizabeth J Oswecki(74) *Attorney, Agent, or Firm* — Andrew F. Young, Esq.;
Lackenbach Siegel, LLP(57) **CLAIM**

The ornamental design for a weld cap, as shown and described.

DESCRIPTION

FIG. 1 is a front elevation view of a weld cap showing my new design.

FIG. 2 is a rear elevation view of FIG. 1.

FIG. 3 is a left side elevation view of FIG. 1.

FIG. 4 is a right side elevation view of FIG. 1.

FIG. 5 is a top plan view of FIG. 1.

FIG. 6 is a bottom plan view of FIG. 1.

FIG. 7 is a right side, front perspective view of FIG. 1.

FIG. 8 is a left side, top perspective view of FIG. 1.

FIG. 9 is rear, bottom perspective view of FIG. 1; and,

FIG. 10 is another right side, front perspective view of FIG. 1 with a visual shield in broken lines shown in a used condition. The portions shown in FIGS. 1-10 are lightly lined for contour only and do not contribute to the claimed design. No claim is made to surface texture of the particular design. The visual shield shown in FIG. 10 is shown in broken lines and forms non part of the claimed design.
